UNITED STATES PATENT OFFICE.

FREDERICK LEU, OF LONG ISLAND CITY, NEW YORK, ASSIGNOR TO MAXMILIAN CALM,
OF BROOKLYN, NEW YORK.

NUT-CRACKING MACHINE.

1,213,510.

Specification of Letters Patent. Patented Jan. 23, 1917.

Application filed November 12, 1915. Serial No. 61,186.

To all whom it may concern:

Be it known that I, FREDERICK LEU, a citizen of the United States, residing at Long Island City, in the county of Queens 5 and State of New York, have invented certain new and useful Improvements in Nut-Cracking Machines; and I do hereby declare the following to be a full, clear, and exact description of the invention, such as will enable others skilled in the art to which it 10 pertains to make and use the same.

This invention relates to nut cracking machines and it has for an object to provide a machine for removing the kernel from a 15 nut having a very thick and hard shell.

A further object of this invention is to provide an improved type of cutter which may be interchangeably carried by said machine to afford a maximum of cutting edge 20 from a single cutter.

Further objects will be apparent from the following specification, appended claims and drawings, in which—

Figure 1 is a perspective view of the complete machine, Fig. 2 is a side elevation of parts of the machine, showing one of the halves removed, Fig. 3 is a cross sectional view as on the line 3—3 of Fig. 2, Fig. 4 is a similar view as on the line 4—4 of Fig. 2, 30 and Fig. 5 is a bottom view, showing parts in section of the head of the machine.

Referring to the drawings, 10 indicates a frame having the legs 11, 12 and 13, and this frame includes a head formed of the halves 35 14 and 15. The legs are disposed so as to form a tripod for the head and are spread at the lower ends to afford sufficient base to prevent tilting of the machine when in operation. The members 14 and 15 are recessed 40 as at 16 and 17 respectively, and have the shoulders 18 and 19 formed therein, between which shoulders, an extension 20 from the leg 13 is clamped. The halves 14 and 15 and extension 20 are rigidly held together 45 by bolts 21, 22 and 23. The forward ends of the halves 14 and 15 terminate in a jaw 24 of which the extension from the member 14 has an overlapping edge 25 which fits in a recessed portion of the member 15 and this 50 overlapping edge 25 forms a support for a cutter which is interchangeably carried thereby in having lugs 26 and a screw 27 to engage opposite faces of a cutter 28 which is triangular in cross section and this cutter

has each of its edges sharpened so that each 55 edge may in turn be used in its capacity.

A swinging jaw 29 which has its rear end bifurcated as at 38 is pivotally mounted upon the bolt 23 and the opposite sides of the extension 20 and the forward end of this 60 jaw terminates in a flat surface upon which lugs 31 are formed to co-act with a screw 39 in holding a cutter 32 which is triangular in cross section properly disposed under the cutter 28.

The legs 11 and 12 have bearings formed thereon between which the lever 33 is pivoted as at 34 and this lever has links 35 pivoted thereto as at 36 upon the pin passing through the upper end of said lever and said links. 70 The links 35 are also pivotally connected as by the pin 37 to the jaw 29. This connection between the lever 33 and jaw 29 together with the particular mounting for said lever forms a toggle for exerting the sufficient force on the cutters 28 and 32 to break 75 the hard shell of the nut and to prevent continued movement of the lever 33, lugs 40 are formed on the upper end of said lever which engage the links 35 in the limit of movement in one direction of this lever. To facilitate in the operation of said lever, a treadle or foot piece 41 is attached to the lower end thereof.

The drawings are submitted for illustrative purposes only and are not intended to restrict this invention to the limited form shown, as modifications may be made within the scope of the appended claims.

I claim:—

1. In a device of the class described, a frame, legs formed on said frame presenting a tripod, a head carried by said legs, said head being formed of halves, each of said halves being recessed, shoulders formed by 95 said recesses, an extension from one of said legs for attachment between said shoulders, a plurality of bolts for securing said halves and extension in fixed relation, a jaw formed by forward extensions of said halves, a cutter of triangular cross section detachably carried by said jaw, a swinging jaw pivotally mounted on one of said bolts, a cutter of triangular cross section detachably carried by said swinging jaw, and a lever pivoted between two of the legs of said frame for actuating said swinging jaw.
2. In a device of the class described, a rela-

tively fixed jaw, lugs formed on said jaw, a screw detachably carried by said jaw, a cutter of triangular cross section detachably carried by said jaw between said lugs and 5 said detachable screw, a swinging jaw, lugs formed on said swinging jaw, a screw detachably carried by said swinging jaw, a cutter of triangular cross section detachably carried by said swinging jaw between 10 said legs and said detachable screw on said swinging jaw, and a lever for actuating said swinging jaw.

3. In a device of the class described, co-acting jaws having relatively flat faces, 15 spaced lugs formed on said faces, said lugs being undercut, a screw detachably carried by each of said jaw members, and an inter-

changeable cutter carried by each jaw member between said lugs and screw.

4. In a device of the class described, a 20 frame comprising a head formed of halves, said halves coacting in forming a jaw, a leg extending from each half of said head, a supplemental leg carried by said head, a swinging jaw carried by said head, and fastening means for said halves, supplemental leg and jaw. 25

In testimony whereof I affix my signature in presence of two witnesses.

FREDERICK LEU.
